UNITED STATES PATENT OFFICE.

SAMUEL L. SMITHERS, OF LINCOLN, NEBRASKA.

RUBBER OVERSHOE.

SPECIFICATION forming part of Letters Patent No. 366,266, dated July 12, 1887.

Application filed March 17, 1887. Serial No. 231,329. (No model.)

To all whom it may concern:

Be it known that I, SAMUEL L. SMITHERS, a citizen of the United States, and residing at Lincoln, in the county of Lancaster and State 5 of Nebraska, have invented certain new and useful Improvements in Rubber Overshoes; and I do hereby declare that the following is a full, clear, and exact description of the invention, which will enable others skilled in the 10 art to which it pertains to make and use the same, reference being had to the accompanying drawings, and to the letters of reference marked thereon, which form a part of this specification.

15 My invention relates to certain improvements in rubber overshoes, the object of my improvements being to prevent the shoe from coming off by slipping down at the heel. I attain this object by means of the devices 20 illustrated in the accompanying drawings, in which—

Figure 1 is a side view of a gentleman's shoe with overshoe and my attachment to the same. Fig. 2 is a plan view of my attachment or heel- 25 strap; and Fig. 3 shows a plan and side elevation of a small metal plate or disk that is secured to the shoe, and to which the heel-strap is riveted.

Similar letters refer to similar parts through- 30 out.

To a rubber overshoe, B, I attach a metal heel-strap, C, running around the heel and secured to the shoe on each side at a point about over the front part of the heel-tap. 35 This strap is pivoted at I, and when raised up, as shown in Fig. 1, it falls into the hollow above the heel and securely prevents the shoe from slipping off.

The heel-strap C is attached to the shoe by means of the two metal disks E, that may be 40 made, as shown in the drawings, with projecting points H H, that are intended to be pressed through the shoe and turned down on the inside; or they may be so made as to be built into the shoe between the lining and the outside 45 covering, only the disk or central portion projecting.

In order to prevent the heel-strap from falling down, the disks E are made with small ridges, as shown at F, with corresponding depressions in the heel-strap C, so located that when the strap is raised to its proper place the ridges F fall into the depressions in the heel-strap, and the disk and strap being held closely together by the rivet I, the strap is prevented 55 from falling, while it may be readily pushed down when desired.

The strap C may be made of any suitable material with metal ends, or it may be covered with leather or rubber, as shown at D, Fig. 1. 60

I claim—

1. In combination with a rubber overshoe, a metallic heel-strap, C, encircling the heel and pivoted to the shoe upon each side, in the manner and for the purpose specified. 65

2. In combination with the metal heel-strap C and rubber overshoe B, the metal disks E, having ridges or corrugations F, when used in the manner and for the purpose set forth.

In testimony that I claim the foregoing as 70 my own I hereto affix my signature in the presence of two witnesses.

SAMUEL L. SMITHERS.
